UNITED STATES PATENT OFFICE.

JOHN DAVID CALDWELL AND IVAN BUSHONG, OF SEATTLE, WASHINGTON.

SHINGLE-TRIMMING MACHINE.

No. 813,946.

Specification of Letters Patent.

Patented Feb. 27, 1906.

Application filed September 14, 1904. Serial No. 224,390.

To all whom it may concern:

Be it known that we, JOHN DAVID CALDWELL and IVAN BUSHONG, citizens of the United States, residing at Seattle, in the county of King and State of Washington, have invented certain new and useful Improvements in Shingle-Trimming Machines, of which the following is a specification, reference being had therein to the accompanying drawings.

In the use of shingle-trimming machines it is customary to saw the opposite side edges of the shingles separately in order to remove the knots therefrom or to straighten such edges or to cut the same to uniform widths and produce what is known as "randoms" or dimensions. This naturally involves a multiplication of operations and a loss of time.

It is the object of this invention to provide in a single structure two sawing-machines whereby the shingle edges may be individually or collectively straightened, as desired, thus overcoming the disadvantages above mentioned.

To these ends the invention consists in certain novel features of construction and combinations thereof, as will be described herein-after with reference to the accompanying drawings, wherein—

Figure 1 is a side elevation, and Fig. 2 is a plan view, of a shingle-trimming machine embodying our invention.

In said drawings the reference-numeral 2 designates the machine-frame, of suitable size and shape, and 3 is a transversely-arranged arbor journaled in boxes 4 of the frame and carrying at its opposite ends a circular saw 5 and a pulley 6.

7 is a shingle-carriage provided with a rear abutment or fence 7' and is reciprocally mounted upon track-rods 8 longitudinally of the frame.

Journalized in boxes 9 of the standards 2' is a transverse arbor 10, carrying externally of the standards a belt-pulley 11, preferably in the same vertical plane with the pulley 6, and intermediate of the standards a plurality of circular saws 12. These saws are connected to their arbor, as by collars 13 and set-screws 13', so as to be adjustably secured longitudinally thereof and at distances apart equal to the widths of shingles it is desired to trim therewith, plus the width of the saw-kerfs.

14 and 15, respectively, are feed and pres-

sure rolls arranged in pairs in advance of and to the rear of the said gang of saws and are each formed with an annular recessed middle portion 18 extending to within a short distance of their extremities, so that when the rolls of each pair are brought together the ends being of greater diameter than the intermediate portions will contact, and a slot is thereby provided between each pair of rolls through which the points of shingles may enter sufficiently far to be frictionally engaged by the rolls. The axles of the top or pressure rolls are journaled at 15' in the outer ends of swinging arms 16, which are pivotally secured to the said standards at 16', while the axles of the lower or feed rolls are journaled in fixed bearings 14' of the standards and are extended at one end therebeyond to carry belt-pulleys 17, which may be advantageously placed to be in line with each other for convenience in belting. To the rear of the back pair of rolls and located slightly below the level of a medial plane projected between the adjacent edges of the said two pairs of rolls is a divided table 19, upon which is received the dimension-shingles coming from the gang-saws and which are shoved over the extreme back end of the table by the next succeeding ones, while the waste or tailings fall through the interstices or over the side edges to a waste pile below.

The operation of the invention is as follows: The shingles which are to be trimmed are severally placed upon the carriage with their thick ends to the rear and resting against the fence thereof and in such transverse position that when the sawyer shoves the carriage forward by hand the shingle being acted upon will be presented either to the saw 5 or out of line with the latter and in line with the gang of saws therebeyond, to which the shingles are severally conveyed from the carriage by the action of the rolls, as before mentioned. Where the shingle is to be trimmed on one or both of the side edges to a width different from that for which the gang-saws are set, then the saw 5 is utilized, and first one edge is cut during the forward travel of the carriage and then withdrawn and again shoved forward to complete the other edge after the shingle has been turned over, and the finished shingle is then thrown off into a pile for bunching. Should, however, the shingles be desired to be cut into the

standard or dimension sizes, corresponding to the positioning of the saws on arbor 10, they are placed upon the carriage in such manner as not to be interrupted by the single saw and are moved forward with the carriage to be acted upon by the rolls, as aforesaid. It will thus be seen that the sawyer can work his stock into shingles which will finish to most suitable widths. For example, should 10 the stock be of width sufficient for cutting two standard-width shingles then he could run that particular shingle through the gang-saws; but where it is of less width than this, but considerably more than enough to make 15 a single standard width, then he can better trim its edges with the single saw, as being less wasteful of the material. It will be thus seen that the present invention furnishes means to provide a considerable saving both 20 in time and material to shingle-manufacturers and marks a decided advance in the art.

Having described our invention, what we claim as new, and desire to secure by Letters Patent, is—

25 1. In a machine of the class described, the combination with the framework, of a plurality of saws mounted upon an arbor, feed and pressure rolls for said saws, a single saw mounted upon another arbor and positioned 30 outside of the plane of the outermost of the aforesaid saws, track-rods mounted on said

frame and extending from in front of to the rear of said single saw and a carriage mounted on said track-rods and adapted to convey the shingles being operated upon to first-mentioned plurality of saws or to the last-named saw, substantially as described. 35

2. In a machine of the class described, the combination with a framework, an arbor journaled therein, a single saw carried on said arbor and located outside the framework, of another arbor mounted on the framework, a plurality of saws mounted on said last-named arbor and a carriage mounted on the framework and adapted to feed material to said 40 single saw and past said single saw to said plurality of saws.

3. In a machine of the class described, the combination with the framework, a plurality of saws carried by an arbor, said arbor, a carriage reciprocally mounted upon said frame, of a table positioned upon the opposite end of the frame to the carriage, said table having an opening therein through which the waste products will fall, substantially as described. 50 55

In testimony whereof we affix our signatures in presence of two witnesses.
